(57) **CLAIM**

The ornamental design for a nut, as shown and described.

DESCRIPTION

FIG. 1 is a perspective view of a front and top of an embodiment of a nut;

FIG. 2 is a perspective view of a rear and bottom of the nut of FIG. 1;

FIG. 3 is a front elevational view of the nut of FIG. 1;

FIG. 4 is a rear elevational view of the nut of FIG. 1;

FIG. 5 is a top plan view of the nut of FIG. 1;

FIG. 6 is a bottom plan view of the nut of FIG. 1;

FIG. 7 is a left side elevational view of the nut of FIG. 1;

FIG. 8 is a right side elevational view of the nut of FIG. 1;

FIG. 9 is a perspective view of a front and top of another embodiment of a nut;

FIG. 10 is a perspective view of a rear and bottom of the nut of FIG. 9;

FIG. 11 is a front elevational view of the nut of FIG. 9;

FIG. 12 is a rear elevational view of the nut of FIG. 9;

FIG. 13 is a top plan view of the nut of FIG. 9;

FIG. 14 is a bottom plan view of the nut of FIG. 9;

FIG. 15 is a left side elevational view of the nut of FIG. 9; and,

FIG. 16 is a right side elevational view of the nut of FIG. 9.

The dash-dash-dash broken lines are included for the purpose of illustrating portions that form no part of the claimed design.

1 Claim, 16 Drawing Sheets
